GYROSCOPIC COMPASS

Application filed September 22, 1930, Serial No. 483,551, and in Germany September 30, 1929.

This invention is an improvement in or modification of that described in the co-pending application of Anschutz-Kaempfe Ser. No. 303,582 filed Sept. 1, 1928 which relates to a gyroscopic apparatus including a gyroscope carrier which has at least one gyroscope with a horizontal axis and is surrounded by a follow up system adapted to be turned by servomotors both about the vertical axis and about the two horizontal principal axes. If this gyroscopic apparatus is installed on board ship, automatic means are operative to so turn the follow up system, as to keep it permanently in an invariable position in space relatively to the gyroscope carrier. For this purpose, the follow up system is turned about the vertical axis and/or about the two horizontal axes, for example, the longitudinal axis and the transverse axis of the ship. As a result, the normally horizontal plane of the carrier is always kept horizontal. By transmission of the turning movements produced by the servomotors on the follow up system to a suitably mounted body, the latter is automatically stabilized against the movements of the ship and the turning movements of the latter may be observed at remote stations. In the embodiment of the invention described in the above-mentioned co-pending application the current of each servomotor is controlled by controlling members which are mounted on the follow up system so that their plane of oscillation is always at right angles to the axis of oscillation co-ordinated with their motor. The controlling members co-ordinated with each servomotor function in case of a displacement relatively to the gyroscope system to so influence an electric system that the servomotor is set in motion and restores the follow up system and the controlling members carried thereby to the original position relatively to the gyroscope carrier. Preferably, conductive faces arranged on the follow up system are used as controlling members, and cooperate with a specially shaped conductive face provided on the gyroscope carrier. Both conductive faces are in electric connection through a poorly-conducting liquid surrounding the gyroscope carrier. A pair of such conducting faces is allotted to each servomotor and is connected in a bridge connection. If the bridge is thrown out of balance through relative displacement of the follow up system and the gyroscope carrier, the potential produced in the diagonal branch of the bridge causes the servomotor to run in such a direction that the conductive faces are brought back again into the normal relative position, and thus equilibrium is restored again within their bridge connections. The farther the follow up system is displaced from its normal position relatively to the gyroscope carrier, the stronger will be the restoring force exerted by the servomotors. For a more detailed description of the operation reference is made to the co-pending application. By the insertion of amplifying apparatus, the sensitiveness of these connections may be increased such that the follow up system deviates by very small amounts only from its normal position, so that it reproduces the movements of the ship about the three principal axes with an accuracy sufficient for the purposes of fine measurement. It is of course necessary in this case that the out of balance of the bridge connections should be brought about by the ship's turning alone, which is to be measured, and not by other causes.

I have now found that, in the arrangement described in the co-pending application, there are considerable difficulties in providing absolutely uniform conditions at the current conducting places for the conductive faces which control the turns about the horizontal axes. The slightest deviation of the edges of the conductive face provided on the gyroscope carrier from the specified circular shape, and the slightest variation in resistance in different points of the said conductive faces cause additional out of balance of the bridge when the ship alters its course. Whereas the conductive faces controlling the turn of the follow up system about the vertical or upright axis always co-operate with the same points of the conductive faces of the gyroscope carrier, the conductive faces carried by the follow up system and controlling the

maintenance of the horizontal position are displaced relatively to the gyroscope carrier and, therefore, will co-operate with different portions of the conductive face of the gyroscope carrier. This introduces a very undesirable source of error, since the unavoidable deviations of the conductive face on the gyroscope carrier from the true geometrical shape are deceptive in indicating variations in the 10 position of the gyroscope system which in reality do not occur.

The object of the present invention is to eliminate these sources of error in order to obtain the highest accuracy in the measurement of the rolling component (B_s) and the pitching component (C_s)—as the relative oscillations of the gyroscope carrier with respect to the ship about the two horizontal principal axes will be denoted for the sake 15 of simplicity—and in their remote transmission for stabilizing purposes. For this purpose, the controlling members, e. g. the conductive faces, which control the current of the servomotors for the rolling component 20 (B_s) and the pitching component (C_s), are likewise turned about the vertical axis to follow the gyroscope system, so that they always cooperate with the same points or portions of the conductive face provided on the gyroscope 25 carrier. Thus, for example, on the follow up system the one pair of conductive faces is arranged in the north-south direction, and the other pair of conductive faces in the east-west direction, and the follow up system is 30 adapted to be so turned about the vertical axis as to maintain an invariable position relative to the gyroscope carrier. The horizontal oscillation axes of the follow up system, however, are arranged stationary with respect to 35 the ship, so that, for example, one may be in the longitudinal direction and the other in the transverse direction of the ship. Consequently, each time the ship's course is 40 changed, the B_s and C_s conductive faces, 45 which are turned about the vertical axis, are displaced with respect to the B_s and C_s oscillation axes co-ordinated with them, and means are provided which permit each of the two pairs of conductive faces to control, in 50 accordance with their angular position relatively to the horizontal oscillation axes, to simultaneously actuate the two co-ordinated 55 servomotors.

This may be explained by an example. Let 60 the ship have a N. W. course and be rolling and pitching at the same time, so that it executes, for example, an oscillation in the E. W. plane. In consequence, only the conductive faces, which are arranged east-west 65 and which are turned correspondingly at the moment, come into operation. By this means, however, the B_s -servomotor effecting the follow up movement about the ship's longitudinal axis and the C_s -servomotor effecting the 70 follow up movement about the ship's trans-

verse axis must be driven in order to enable the follow up system to follow in the shortest path the relative movement of the gyroscope carrier with respect to the ship.

I have, therefore, provided a special apparatus by means of which the B_s and C_s conductive faces operate on the servomotors. This apparatus comprises a transformer having a stator and a rotor which is turned together with the follow up system about the 75 vertical axis and will be referred to herein-after as "co-ordinate transformer". With the current impulses supplied by the two pairs of conductive faces, a uniform alternating field is built up in the rotor of the transformer, which field then produces in pairs of coils of the stator, which are stationary relatively to the ship, component currents which are supplied to the two servomotors.

A constructional example of my invention is illustrated more or less diagrammatically in the accompanying drawings, in which

Fig. 1 shows the gyroscope compass in a section transversely of the ship's longitudinal axis, the electrical connections being omitted;

Fig. 2 shows the gyroscopic compass in a vertical section in the direction of the ship's longitudinal axis, with a circuit diagram of the co-ordinate transformer, the spherical gyroscope system being shown in elevation in both figures, the gyroscope transformer being omitted;

Fig. 3 is a wiring diagram with a horizontal section through the gyroscope system;

Fig. 4 is a wiring diagram with a vertical section through the gyroscope system;

Figs. 5 and 6 show a wiring diagram of the co-ordinate transformer in different positions;

Fig. 7 illustrates the attachment of the co-ordinate transformer in a partial elevation which is similar to Fig. 2.

In the supporting frame 1 of the gyroscopic compass are mounted pins 2, lying transversely of the ship's axis, of a Cardan ring 3, which in turn is provided with bores for the bearings of pins 4, lying in the longitudinal direction of the ship, of the liquid container 5. In the cover 6 of the container, a vertical pin 7 is rotatably mounted and carries by means of a plurality of brackets 8 an upper encasing bowl 9 and a lower encasing bowl 10, which are held together by distance pieces 12 and bolts 11. The ball-shaped gyroscope carrier 13 floats freely between the encasing bowls 9 and 10 without contacting them anywhere, and a plurality of gyroscopes are provided in the spherical casing of the said carrier, which therefore always maintains an invariable position relatively to the horizon and the meridian. Around the equator of the spherical gyroscope system 13 there extends an electrically conducting strip 14, one half of which is interrupted in the centre by an insulating 110

115

120

125

130

face 17, so that it consists only of two narrow conducting bands 15 and 16, while the other half is made full width.

The follow-up movement of the follow-up system 9, 10, 12 surrounding the gyroscope system 13, is effected by three alternating current motors 24, 31 and 33, the electric motor 24 being mounted on the cover of the casing and driving by means of the worm 28 a wormwheel 29, secured to the pin 7, in order to turn the follow up system about the vertical axis, when the ship's course is altered. The electric motor 33, located on the base frame, drives by means of the worm 34, a worm segment 36, which is fixed to the pin 2, so that by this means the Cardan ring 3 carrying the pins 4, is turned in accordance with the pitching of the ship while the electric motor 31 for turning the casing in accordance with the rolling of the ship, is carried by a bracket 48 on the Cardan ring 3 and drives by means of a worm 35 a worm segment 37 fixed to the pins 4. The three motors are controlled by resistance variations in a manner explained more fully in the co-pending application. Thus, the servomotor 24 is controlled by two conductive faces 18 and 18', displaced relatively to one another by 180° (Figs. 2 and 3), and carried by distance pieces 12 in a manner such that they lie opposite the edges 19, 19' of the equatorial conducting face 14. Fig. 2, which is a vertical section, shows diagrammatically the two conductive faces 18 and 18' in their normal position relatively to the edges 19 and 19'.

Current is supplied to the gyroscope system by a conducting face 25, which is carried by the follow-up system and is connected to a terminal 26 of a source of alternating current. The current then passes through the supporting liquid to a conducting face 49 on the floating casing 13, which face is connected to the conducting face 14. From the conducting face 14, the current passes to the conducting faces 18 and 18' of the follow up system in two branch currents, which flow through two opposing inductance coils 20 and 21 (Fig. 3) and are then united to return to the other terminal 27 of the source of alternating current. The resistances between the conducting faces 18 and 19 on the one hand and 18' and 19' on the other, and the alternating current resistances 20 and 21 constitute the alternating current bridge, the diagonal points of which are denoted in Figure 3 by 22 and 23. As soon as the follow up system 9, 10, 12 is turned about the vertical axis relatively to the spherical gyroscope system 13, the resistances between the faces 18, 19 and 18' and 19' become unequal, so that an alternating potential is produced between the points 22 and 23. This controls an amplifying apparatus (not shown) which feeds the motor 24 so that the latter is set in motion and drives the follow-up system in

such a direction and by such an amount that the normal position shown in Fig. 2 is again reached and the contact resistances therefore again become equal. The details of the connections and the supply of current to the motor 24 are not shown for the sake of simplicity. In this connection reference may be made to German Patent No. 466,098 in which a more detailed disclosure of all this is given.

For the follow up turn of the follow up system about the two horizontal axes of the pins 2 and 4, there are provided pairs of conductive faces, fixed to the follow up system one in the north-south plane and the other in the east-west plane.

In Fig. 1 only the pair of conductive faces 30 is visible in section, while the other pair of conductive faces, indicated at 32, is hidden by the ball-shaped casing 13 of the gyroscope system. In Fig. 2 the pair of conductive faces 32 is visible in section, while the conductive faces 30 are hidden behind the casing and indicated by dotted lines. The resistance encountered by the current passing between the conductive face 14 of the gyroscope system on the one hand and the two co-ordinated conductive faces 30 or 32 on the other vary if oscillations of the follow up system are caused by the rolling or pitching of the ship. Bridge connections are made to the two pairs of conductive faces 30 and 32, as shown in Fig. 4, but the potentials produced are not directly employed for the control of the motors 31 and 33. For, since the pairs of conductive faces 30 and 32 are turned by the servomotor 24 about the vertical axis, they take up variable positions relatively to the axes of oscillation of the pins 2 and 4, so that the current impulses which they produce, must be supplied, according to their position, in varying proportions either to the motor 31 or motor 33 or to both motors at the same time. The alternating currents taken from the two pairs of conductive faces 30 and 32 are therefore supplied to the co-ordinate transformer T shown in Figs. 2, 5, 6 and 7. The said transformer consists of a four-pole, rotating magnetic field, connected with the pin 7 as indicated in Fig. 7, so that it partakes of the turning of the said pin and surrounds an armature which is mounted stationary relatively to the vertical axis, i. e. for example, it is carried by the cover 6.

The windings 38 and 39 of two opposite pole-pieces of the magnetic field are constituted by the inductance coils which are connected to the conductive faces 30, see Fig. 2, while the windings 40 and 41 of the other two pole-pieces are fed by the conductive faces 32. The armature is constituted by a slotted drum of laminated iron sheets, and receives two crossed coils 42 and 43 which are electrically at right angles to one another. The terminals of these two secondary windings

are connected to four brush rings 44 to 47 which are connected either directly, or preferably through amplifying apparatus (not shown), to the motors 31 and 33 in the manner 5 described in the German Patent No. 466,098. If the ship holds a course, such that the armature assumes with respect to its magnetic field the position shown in Fig. 5, a potential difference in the coils 38 and 39 produces an 10 alternating current of corresponding phase and strength in the secondary winding 42 only, while the winding 43 remains de-energized. In like manner potential differences in the windings 40 and 41 affect solely the 15 winding 42.

Upon a change in the course of 45°, the position shown in Fig. 4 is attained, in which a potential difference of the coils 38 and 39 induces a current both in the winding 42 and 20 in the winding 43, so that the two motors 31 and 33 are set in motion and with the same starting torque. By this means, the follow up system is turned about its axes along the shortest path to follow the movement of the 25 gyroscope system relatively to the ship, because a difference between the potentials of the coils 38 and 39 is produced by the follow up system tilting about the axis L—L indicated in Fig. 4, which, however, can only be 30 eliminated in the shortest path by a simultaneous and equally rapid turning about the axes M—M and N—N. The axes M—M and N—N correspond to the axes of the pins 2 and 4, while the axis L—L gives the vertical plane 35 in which the conductive faces 30 are situated.

Upon a further change of course of 45° in the same turning direction, a position is attained which corresponds to Fig. 3 but in which the windings 42 and 43 have 40 changed their rôles. This, in fact, is necessary, since in the meantime the coils 38 and 39 and the conductive faces 30 connected thereto, have wandered from the rolling to the pitching plane of the ship, while the rolling and pitching motors 31 and 33 remain 45 stationary relatively to the ship.

Whatever position may be considered, there is always a distribution of the current impulses between the two motors 31 and 33, 50 which are stationary relatively to the ship, such as would be obtained if the conductive faces were likewise mounted stationary relatively to the ship and were connected directly to the motors, for example, in the manner 55 described in the co-pending application. By means of the co-ordinate transformer, the fact that the conductive faces 30 and 32 are turned relatively to the ship when the course is altered is taken into account.

The fields produced by the coils 38 and 39 on the one hand and by the coils 40 and 41 on the other are superimposed to form a unitary field which is resolved by the windings 60 42 and 43 into components, corresponding to

the transformation into the other system of co-ordinates.

An essential feature of my invention thus consists in that the torques produced by servomotors operate about axes stationary relatively to the ship but are controlled by members adapted to vary their position relatively to the said axes. 70

What I claim is:—

1. A gyroscopic compass comprising a gyroscope carrier having at least one gyroscope with a horizontally disposed axle, a follow-up system surrounding said carrier and adapted to be turned about the three principal axes, including two normally horizontal axes, servomotors for turning said system about the latter axes, members mounted on said follow-up system to control said servomotors, and a transformer comprised of a stator and a rotor coupled to said follow-up system for common rotation therewith about its vertical axis, said transformer being connected to said members and to said servomotors whereby the latter are caused to restore said follow-up system along the shortest path 90 to a predetermined position relative to said gyroscope carrier. 95

2. A gyroscopic compass comprising a gyroscope carrier having at least one gyroscope with a horizontally disposed axle, a follow-up system surrounding said carrier and having a normally vertical pivot, a support in which said pivot is journaled and which is tiltably mounted about two horizontal axes 100 perpendicular to one another, three servomotors, two for turning said support about the last mentioned axes and one for turning said carrier about said pivot, members mounted on said follow-up system for controlling said servomotors, a transformer comprised of a stator and a rotor, the latter being coupled to said follow-up system for common rotation about the vertical axis thereof, said transformer being connected on the one side to those of said members which are co-ordinated to the two first-mentioned servomotors and on the other side to the latter whereby said servomotors are caused to restore said follow-up system along the shortest path to a predetermined position relative 110 to said gyroscope carrier. 115

In testimony whereof I have affixed my signature.

DIPL. ING. OSKAR RICHTER.
